PENCIL SHARPENER

Alvin L. Fenton, Omaha, Nebr.

Application June 10, 1937, Serial No. 147,554

4 Claims. (Cl. 120—96)

This invention appertains to new and useful improvements in pencil sharpeners whereby pencils can be sharpened without any manual effort on the part of the operator.

5 An important object of the invention is to provide a pencil sharpener wherein the sharpener elements are mounted vertically and into which a pencil is engageable from a vertical position, to the end that there will be a uniform application 10 of pressure of the pencil against the sharpener elements which will result in less strain on the motor and less irregular wear on the sharpening elements.

15 Another important object of the invention is to provide a pencil sharpener which is positive acting and which is constructed in such a manner as to not be susceptible to the ready development of defects.

20 These and various other important objects and advantages of the invention will become apparent to the reader of the following specification.

In the drawings:

Figure 1 represents a bottom plan view of the sharpener with a portion broken away.

25 Figure 2 represents a vertical sectional view of the sharpener.

Figure 3 is a top plan view of the shavings collecting pan.

30 Figure 4 is a fragmentary detailed sectional view taken substantially on the line 4—4 of Figure 1.

Figure 5 is a plan view of the assembled sections of the emery wheel.

Figure 6 is an end elevational view of the emery wheel.

35 Figure 7 is an inside elevational view of one of the sections of the emery wheel.

Referring to the drawings wherein like numerals designate like parts, it can be seen in Figure 2 that numeral 5 represents the electric motor which has a wall attachable base portion 6.

40 Numeral 7 represents a shell having the closed top *a* and the inturned flange *b* at its lower open side. Hook members 8 are provided on the bottom of the top *a* and these engage into the arm members 9 on the motor base 6 as shown in Figure 4.

45 An annular channeled shaving collector 10 is inwardly flanged as at 11 and these flanges 11 as shown in Figure 3 are provided with bayonet slots 12 for receiving the pins or screws 13 which depend from the flange *b* at the bottom of the shell 7.

50 A cross member 14 is provided at the bottom of the shell 7 for supporting the switch generally referred to by numeral 15 and this switch is provided with the actuating stem 16 extending into

the pencil receiving guide tube 17. At the tube end of the stem 16 a button-like head 18 is provided on the stem so that when a pencil 19 is inserted into the tube 17 the stem 16 will be pushed inwardly to close the switch 15 and thus 5 result in the energization of the motor 5.

On the armature shaft 20 of the motor 5 is the emery wheel structure 21 which consists of a pair of sections 22—22 each provided with a tapering groove 23 therein for receiving and 10 forming the pointed end of a pencil, the sections 22 are provided with openings 24 therethrough and through these openings are disposed the bolts 25 equipped with nuts 26 whereby the sections are attached to the flanged collar 27 secured to the 15 said armature shaft 20.

While the foregoing specification sets forth the invention in specific terms, it is to be understood that numerous changes in the shape, size and materials may be resorted to without departing 20 from the spirit and scope of the invention as claimed hereinafter.

Having described the invention what is claimed as new is:

1. In a pencil sharpener, a shell, a sharpener unit in the shell having a vertically extending 25 pencil receiving inlet, said shell having a vertically extending pencil guide aligned with the said pencil receiving inlet of the sharpener unit, said shell being provided with a bottom through which the guide extends.

2. In a pencil sharpener, a shell, a sharpener unit in the shell having a vertically extending pencil receiving inlet, said shell having a vertically extending pencil guide aligned with the said pencil receiving inlet of the sharpener unit, said shell being provided with a bottom constructed 35 to form a shavings receptor and having a pencil receiving opening therein.

3. In a pencil sharpener, a shell, a sharpener unit in the shell having a vertically extending 40 pencil receiving inlet, said shell having a vertically extending pencil guide aligned with the said pencil receiving inlet of the sharpener unit, said shell being provided with a bottom constructed to form a shavings receptor, and through 45 which the guide extends.

4. In a pencil sharpener, a shell, a sharpener unit in the shell having a vertically extending pencil receiving inlet, said shell having a vertically extending pencil guide aligned with the said 50 pencil receiving inlet of the sharpener unit, said shell being provided with a bottom through which the guide extends, said bottom being of annularly 55 channeled construction through the central portion of which the guide extends.

ALVIN L. FENTON.
